UNITED STATES PATENT OFFICE.

CASPAR WEBER, OF CHICAGO, ILLINOIS.

VELOCIPED.

SPECIFICATION forming part of Letters Patent No. 333,268, dated December 29, 1885.

Application filed September 29, 1885. Serial No. 178,495. (No model.)

To all whom it may concern:

Be it known that I, CASPAR WEBER, a citizen of the United States of America, residing at Chicago, in the county of Cook and State 5 of Illinois, have invented certain new and useful Improvements in Velocipedes, of which the following is a specification, reference being had therein to the accompanying drawings.

10 My invention relates to improvements in tricycles.

The object of the invention is to improve the propelling mechanism of such devices, thereby rendering the operation thereof simple and effective.

15 To the accomplishment of the above the invention consists of certain novel devices and combination of devices, as will be described and claimed.

20 Reference will be made to the accompanying drawings, in which Figure 1 is a side elevation of my improved tricycle; Fig. 2, a top plan thereof; Fig. 3, longitudinal section through parts thereof, and Fig. 4 an end elevation.

25 Like letters refer to like parts in each view.

The frame-work of the machine consists of cross pieces A A', connected at their ends to form bearings for the axle B, a cross-piece, 30 C, and a longitudinal strip, D, connecting cross-pieces A A' and C.

E E represent the large wheels mounted upon axle B, and F the small front wheel, the axle G of which has bearings in a hanger, H, 35 as shown. Hanger H at its upper end is provided with a pin, H', which passes up through an opening formed in cross-piece C, and to the upper end of which a foot-lever, K, is secured. Foot-lever K extends rearwardly and 40 is in convenient reach of the occupant, who is thus enabled to turn the front wheel and thereby guide the machine.

L is the seat, which is preferably mounted upon the longitudinal strip D, before referred 45 to.

Mounted upon cross-pieces A A' are the uprights M M, preferably of the form shown, and one upon each side of the machine. Mounted in the upper ends of uprights M is a shaft, N, 50 which protrudes at each end beyond the uprights. Secured to shaft N, at points between uprights M, are two rods, O, provided near

their lower ends each with a handle, O', such handles being within convenient reach of the occupant. Secured pivotally to each rod O, 55 at the point shown, is an arm, P, which arms extend forwardly, and at their front ends are bifurcated, as shown. Pivoted in the bifurcated end of each arm P is a crank-arm, R, each of which is secured at its lower end upon a short stud or shaft, S, passed through the upturned ends of cross-piece C.

T T represent two pieces, bent to a form substantially like the letter C. Each piece T is provided with a cross-strip, V, provided at 65 its center with an opening through which the outer end of stud or shaft S is passed, the pieces T being thus mounted upon such shafts and adapted to revolve therewith.

By the arrangement of parts as thus far described, it will be seen that when the parts occupy the position shown in full lines in Fig. 1, if the rods O are forced back the pieces T will be partly revolved to carry them to the position shown in dotted lines in the same 75 figure. At one end, as shown, each piece T is provided with a weight, T', the object of which will be described. Each piece T is grooved on its circumference, and in the groove two cords, W W', now to be referred to, rest. 80

By reference to Fig. 3 it will be seen that cord W is secured to piece T at a point near the opposite end to that upon which weight T' is mounted. This cord is then carried back, and after passing partly around a grooved pulley, X, mounted loosely upon axle B, is secured thereto. Cord W' is secured nearer the opposite end of piece T, extends back, and is passed up around the pulley X, to which it is secured. By this arrangement it will be seen if piece T 90 is revolved to elevate its weighted end the cord W' will serve to revolve pulley X, while if said piece is revolved in the opposite direction the pulley will be revolved, its direction being likewise reversed through the medium of cord W. 95 Each pulley X is hollow and provided upon one side with an open face to prevent its contacting with cross-pieces A A'; but upon its opposite side is formed with a plate, upon which its hub X' is formed.

100 Mounted upon the side plate of each pulley X is a pawl, Y, the free end of which is depressed by means of a spring, Y'. Pawl Y is arranged to engage with the teeth of a ratchet,

B', formed upon the inner end of the hubs of wheels E, the teeth of such ratchet being so arranged that it will be revolved by pawl Y only upon the forward revolution of pulley X, such revolution being made as the weighted ends of pieces T are lowered.

Secured to each end of shaft N, hereinbefore referred to, is a forwardly-extending rod, C', provided upon its outer end with a weight, C².
10 An arm, D', is also secured to each end of shaft N, such arms being arranged at right angles to rods C', and having secured to their upper ends each a rearwardly-extending rod, E', provided with weights E² at their outer ends.

15 F' represents a foot-rest mounted upon cross-piece C.

The operation of the device is as follows: Supposing the pieces T to occupy the position shown in full lines in Fig. 1, which is their normal position, the rods O will be drawn forward, as shown. It being desired to propel the machine the operator forces the rods back, and by so doing he causes the pieces T to revolve until the weighted ends of said pieces occupy 25 the position shown in dotted lines in the same figure. By the revolution of pieces T, as described, the cords W' are pulled upon, and through their medium the pulleys X are revolved. The direction of the revolution of pulleys X in this instant is such that the pawl Y will slip over the ratchet B' without revolving it, and will occupy the position shown in dotted lines. The backward pressure on rods O being removed, the weights secured to what 30 this time are the upper ends of pieces T, will serve to cause such pieces to revolve in the opposite direction, the rods O being drawn forward at the same time. As this reverse revolution of pieces T is secured, the cords W will cause

the revolution of pulleys X also in a reverse direction to that first described. As pulleys X are thus revolved, the pawl Y will engage with ratchets B' and cause them to revolve, and such ratchets being mounted upon the hubs of wheels E, the wheels will be revolved and the machine 40 propelled forward, the operation being repeated. The weighted rods C' and E' during the operation described will change position, as indicated in dotted and full lines in Fig. 1, and they serve in the capacity of fly-wheels to 50 the machine.

What I claim is—

1. The combination, with the main wheels of a tricycle, suitable curved and weighted pieces, and intermediate connections, of suitable means 55 for elevating the weighted ends of such pieces, as set forth.

2. The combination, with main wheels E, curved and weighted pieces T, and intermediate connections, of crank-arms R, and rods P 60 O, as set forth.

3. The combination, with wheels E, carrying ratchets, and grooved pulleys X, carrying spring-depressed pawls Y, of cords W W', curved and weighted pieces T, and suitable 65 mechanism for elevating the weight ends of such pieces, as set forth.

4. The combination, with wheels E, curved and weighted pieces T, and suitable intermediate connections, of crank-arms R, rods P O, 70 shaft N, and weighted rods C' E', as set forth.

In testimony whereof I affix my signature in presence of two witnesses.

CASPAR WEBER.
